UNITED STATES PATENT OFFICE.

WILLIAM M. FULLER, OF CROWN POINT, NEW YORK, ASSIGNOR OF ONE-THIRD TO WALTER C. WITHERBEE, OF PORT HENRY, NEW YORK, AND ONE-THIRD TO MILO M. WINTERS, OF CROWN POINT, NEW YORK.

GRAPHITE-SEPARATOR.

No. 894,879.

Specification of Letters Patent.

Patented Aug. 4, 1908.

Application filed November 25, 1905. Serial No. 289,059.

To all whom it may concern:

Be it known that I, WILLIAM M. FULLER, residing at Crown Point, in the county of Essex and State of New York, have invented certain new and useful Improvements in Graphite-Separators, of which the following is a full, clear, and exact description, such as will enable others skilled in the art to which it appertains to make and use the same.

10 This invention relates to improvements in that class of machinery known as ore separators, and while it is applicable to various other varieties of ores, it particularly concerns the separation of graphite from its matrix.

One object of this invention is to devise a compact self contained ore separator in which all the parts are so connected and positioned that the full individual advantages 20 of each will be wholly realized and further augmented by reason of their mutual coöperation as a whole, whereby the machine speedily and effectually operates to effect an economical segregation of the valuable concentrates and useless gangue.

Another object is to formulate a separator composed of parts, simple in nature and adapted for production at small cost, so constituted that they may be easily assembled 30 to form a practical means for handling ores, which is capable of being continuously operated by the application of little power, and which, while not dependent upon the use of water, will operate without waste thereof to 35 efficiently separate ores of various sorts.

Still another object of the invention is to produce a machine of the above nature, which, because of the convenient shape and mass of the component elements, may be 40 readily transported to otherwise inaccessible mining regions and there put together with ease by the usual workers of such region.

Another aim is to have the parts of durable and wear resisting construction and so 45 united to other parts that they may be readily replaced when worn out.

Additional objects and advantages which this invention has in view will be set forth in describing one mode of practically embodying the same and others should be thereby made obvious.

With the aforesaid and other ends in view, the invention accordingly consists in the combinations of parts, features of construc-

tion and arrangement of elements hereafter 55 more explicitly shown as an exemplification of a preferred embodiment thereof, and in order that the invention may be more fully understood and the underlying principles thereof made comprehensible to all persons 60 skilled in its relating arts, I have appended drawings in which like letters of reference denote corresponding parts throughout all the views of which:—

Figure 1 is a view in sectional elevation 65 showing the general arrangement of the parts constituting the separator and illustrates the means for admitting ore to the screen and of finally emitting the same after its segregation has been effected. Fig. 2 is a plan view 70 of the parts as shown in Fig. 1. Fig. 3 is a section taken on line *a*—*a* of Fig. 1 showing the arrangement of elevators and showing the sand slide. Fig. 4 is a section on line *b*—*b* of Fig. 1 showing the graphite slide together with the elevator for the material falling thereon, and illustrating the mode of operation of the sweeper. Fig. 5 is a general perspective view in detail of a form of sweeper such as I employ in practice. Fig. 80 75 80 shows in perspective one of the hoops affixed to the interior of my cylindrical screen, showing the inclined arrangement of the scoops or vanes thereon which have for one object the acceleration of the ore to be treated through the machine.

Making reference now to such figures, 1 indicates a screen of suitable construction, preferably adapted to being continuously agitated. In the herein shown embodiment 90 this screen is cylindrical in form and is carried upon a suitable supporting axis 2 journaled at the ends to the frame of the separator. A driving gear 3 of any suitable construction serves to actuate the revolvably 95 mounted screen.

The ore to be separated is introduced into the upper end of the screen by means of a hopper 4 mounted in the frame of the separator and having an exit orifice leading into 100 the interior of the cylindrical screen. To expedite the flow of the ore through and over the surface of the screen, it is given a slightly inclined position the degree of which may be governed by the class of work to be performed thereby. A series of scoops or vanes 5 are carried by the screen in its rotation and because of the spiral or inclined disposition

and shape of such scoops, they serve to accelerate the motion and travel of the ore along the surface of the screen. Such scoops or vanes may be mounted in any suitable manner upon the screen; in practice I preferring to interiorly attach them to annular hoops which are affixed to the screen, although it is well within the province of this invention to otherwise mount such scoops.

- 10 Mounted so as to brush over the surface of the ore and screen are one or more sweepers 6 which preferably are constructed after the fashion of an elongated brush carrying bristles 7 of any suitable substance, which bristles travel over and sweep the underlying surface of the screen and thereby serve to keep the same clear of ore and scour the latter, the gangue of which is thereby assisted through the meshes of the screen. Such 15 sweepers may be maintained in contact with the screen in any suitable manner, though possibly the expedient shown is the simplest. This consists in providing a sweeper with arms 8 having in general a hook of U-shape, 20 between the members of which is engaged the axis 2. A sweeper so mounted will by gravity be kept in contact with the underlying ore carrying surface of the screen and provision is made at the same time for compensating for such wear of the bristles as 25 may occur in the use of the separator. Sweepers mounted in this manner may be readily detached when worn out and replaced by new ones. It is obvious that in lieu of 30 the particular form of sweeper here shown other variations accomplishing the same purpose may be resorted to, although certain advantages are inherent in that above described.
- 35 A suitable means for removing the gangue passing through the screen is provided. This consists in a slide 9 upon which the gangue falls from the overlying screen and by which it is directed to the discharge orifice 45 10 into the well 11 of the sand conveyor chamber 12. Suitably mounted within such chamber is a conveyer of any desirable construction but the elevator which I have designated by 13 is best suited for ordinary purposes. This elevator consists of an endless 50 bucket carrying belt traveling around upper and lower pulleys, carrying the waste from the bottom to the top of the separator and there discharging it. It will be observed 55 that this arrangement permits of a continuous removal of the waste gangue from a separator full of water without any waste of the latter which is frequently of such importance in districts where water is scarce.
- 60 The concentrates are ejected from the end of the screen into chamber 14, falling upon slide 15 and thereby directed through the orifice 16 in the partition 17. From such orifice 16 the concentrates pass into well 18 65 of the graphite or other concentrate elevator

chamber 19. The elevator 20 therein mounted is similar in construction and arrangement to the gangue elevator and while the same may be driven independently of the latter it is obvious that the upper driving pulleys of 70 both elevators may be mounted upon and actuated by a common shaft, if desired.

It is desirable that some provision be made for preventing the concentrates emitted from the end of the screen from coursing back on 75 the under side of the same, and for this purpose I provide an adjustable sliding connection consisting of an annular flange 21 adjustably mounted upon the end of the screen. Co-acting therewith is a member 22, in close 80 contact with which slides the adjustable flange. Such member 22 forms with the partition to which it is affixed a sort of flange box which effectually prevents the graphite or other concentrates from returning or 85 working back under the screen.

While the separator as herein described is capable of doing excellent work on dry ores under certain circumstances, under other conditions it is preferable that the washing 90 and separation take place under water. To this end I provide a water outlet 23 so that the water line of the apparatus will be sufficiently above the ore carrying surface of the moving screen to insure good work. Under 95 these circumstances the ore to be treated and the desirable amount of water will be washed into the hopper 4, onto the moving screen and through the apparatus. The excess water will flow from the outlet 23 while the concentrates and gangue will through the aid of the elevators before mentioned pass from ori- 100 fices 24 and 25 respectively.

This invention is particularly adaptable for the separation of ore in which the concentrates are of a tougher and less brittle nature than their matrix and which are of such relative specific gravity thereto that a "flo- 105 ation" separation may be used.

Graphite is segregated from its matrix 110 very quickly and efficiently by this invention, especially when it is of the foliated variety occurring in minute scales in cleavage planes of quartzite. Such ore is reduced by crushing to a sort of sandy gangue containing 115 intermingled therewith the fine scales of graphite. When such mass passes over the screen the sand which because of its greater specific gravity seeks the bottom, passes through the screen, while the graphite crys- 120 tals tend to form an overlying layer and are washed along away from the sand and saved. Other graphitic ores, such as those in which the matrix is a mica schist, calcite, shale, 125 clay, lime stone, or the like may be also effi- ciently treated by this device. In some cases the course of separation may be reversed or otherwise altered; that is, the concentrates may be of a nature best adapted to pass through the screen in the first instance while 130

the gangue separated therefrom will be washed away without passing through such screen, although this invention is especially adapted for the application first described.

5 As many changes could be made in the above construction and many apparently widely different embodiments of my invention could be made without departing from the scope thereof, I intend that all matter 10 contained in the above description or shown in the accompanying drawings shall be interpreted as illustrative and not in a limiting sense.

Having described my invention, what I 15 claim as new and desire to secure by Letters Patent is:

1. In an ore separator, a tank adapted to contain water, an inclined rotary screen adapted to be partly submerged in the water 20 having an axle extending through its longitudinal center, a brush sweeper therefor depending from said axle and having a vertically yielding connection therewith, a means for producing a relative movement between 25 said members, and a stationary receptacle underlying said screen and arranged to receive material passing through said screen.

2. In an ore separator, a tank adapted to contain water, a revoluble cylindrical screen 30 adapted to be partially submerged, inclined scoops interiorly carried thereby and revoluble therewith, and radially disposed pliable brushes yieldably resting on said screen and gravitally restrained within the 35 merged area against revoluble movement therewith.

3. In an ore separator, a tank adapted to contain water, a revoluble cylindrical screen adapted to be partially submerged having 40 an axle therethrough and interior hoops, inclined vanes carried by said hoops and revoluble therewith, and pliable brushes intermediate said hoops and freely suspended from said axle in contact with said screen 45 within the submerged area thereof.

4. In an ore separator, a tank adapted to contain water, a revoluble cylindrical screen adapted to be partially submerged having 50 end openings for the coursing of ore and a plurality of internal hoops, inclined vanes mounted on said hoops and revoluble with said screen for urging the ore along, an axle carrying said screen, and sweepers loosely resting within the submerged area on said 55 screen intermediate said hoops and having connections with said axle freely shiftable thereon and thereby maintained in upright position.

5. In an ore separator, a revoluble cylindrical screen adapted to be partially submerged; means for feeding ore into the interior of said screen, a brush sweeping the interior of said screen within the submerged area, an underlying receptacle for the gangue 60 passing therethrough, a receiver for the con-

centrates delivered from the end of said screen, an annular flange encircling the end of said screen, and a partition through which the flanged end of said screen protrudes and separating the aforesaid receptacle and receiver and in sliding close contact with said flange to prevent admixture of the gangue and concentrates.

6. In an ore separator, a tank adapted to contain water having a pair of parallel ore receiving chambers, the one on the one side and the other on the other side, an elongated rotary cylindrical screen between said chambers adapted to deliver concentrates at its distant end and enabling the gangue to pass 80 through its meshes, said screen being adapted to be partially submerged, a brush sweeping the interior of said screen within the submerged area, an underlying slide discharging into the one chamber, an elevator for receiving the gangue discharged by said slide, and a transversely disposed slide adjacent the end of said screen for receiving the concentrates therefrom and arranged to discharge into the other chamber.

7. In an ore separator, a tank adapted to contain water having a pair of parallel elongated ore receiving chambers, the one on the one side and the other on the other side, a revolubly mounted elongated cylindrical 95 screen adapted to be partially submerged arranged intermediate said chambers, an underlying slide having its upper end co-extensive in length with said screen for the reception of the gangue passing through said screen, 100 and adapted to deliver said gangue into the other chamber, and a separate chamber adjacent the delivery end of said screen containing a relatively narrow slide for the reception of concentrates passing thereover 105 and adapted to deliver said concentrates into the one chamber, the end chamber being provided with an overflow orifice opposite the delivering end of said screen and approximately level with water line of said screen.

8. In an ore separator, a revoluble cylindrical screen having end openings for the passage of ore, an axle extending interiorly through said screen and journaled in suitable bearings mounted on the frame of the separator, inclined vanes mounted on hoops interiorly carried by and bracing said screen, sweepers intermediate said hoops and consisting of a brush portion resting on said screen and hook-shaped extensions loosely engaging said axle, a slide underlying said screen for directing gangue falling therethrough, a separate slide adjacent an end of said screen for directing concentrates emitted therefrom, a relatively movable oretight partition intermediate said slides and consisting of an annular flange adjustably encircling said screen and sliding in a suitable flange box, conveyers for carrying material from the aforesaid slides to suitable discharge outlets,

and an inclosing casing having a water outlet slightly above the ore-carrying surface of said screen, whereby ore passing through the separator will be washed under water.

5 9. An ore separator comprising, in combination, a tank adapted to contain water, a transverse partition adjacent one end thereof and forming a gangue receiving chamber, a revolute cylindrical screen having an end 10 passing through an opening in said partition and terminating in said chamber; an annular

flange loosely carried by the end of said partition, and a segmental slide plate coacting with said flange to prevent an admixture of portions of the gangue with the concentrates. 15

In testimony whereof I affix my signature, in the presence of two witnesses.

WILLIAM M. FULLER.
